 ville, Conn., a corporation of Massachusetts

Application November 20, 1936, Serial No. 111,767

17 Claims.

(Cl. 139—7)

This invention relates to Axminster looms, and particularly to improvements in the mechanism employed for conducting the pile yarns to the weaving point.

5 In looms of this type, the pile yarns are carried in a large number of separate tube frames, one for each row of pile tufts, and each having a spool on which the yarn is wound and a set of tubes which assists the wiping-in of the pile 10 yarn between the ground warps. These tube frames are conveyed to the loom above the weaving point on a chain carrier which heretofore has moved intermittently to cause each successive link or section of the chain carrying an 15 individual tube frame to pause in a predetermined position above the weaving point during the interval necessary for certain transferring mechanism to remove the tube frame from the carrier, conduct it to the weaving point and return it to the carrier, after which the carrier is advanced another link or section for the 20 transference of the next succeeding tube frame, and so on.

The intermittent movement of the carrier carrying the large number of heavy tube frames 25 is obviously a disadvantage in the loom operation but has heretofore been considered necessary because of the operation of the transferring mechanism.

30 It is the primary object of the present invention to improve on the loom operation by driving the carrier with tube frames continuously at a predetermined constant rate of speed relative to the weaving cycle and to that end I 35 have devised transferring mechanism having the capacity of taking a tube frame from a section of the carrier when it is in one position, conducting it to the weaving point and returning it to the same section of the carrier after it has 40 reached an advanced position.

In the accompanying drawings:

Fig. 1 is a front elevation view of an Axminster loom embodying my invention;

Fig. 2 is a side elevation view of the loom as 45 seen from the needle side;

Fig. 3 is a detail elevation view of the chain sprockets and clutch arms as seen from the needle side;

Fig. 4 is a detail elevation view of the chain driving gears;

Fig. 5 is a perspective view of portions of the transferring mechanism as viewed from the needle side;

Fig. 6 is a detail elevation view of the latch

mechanism on either end of each tube frame for holding the tube frame in the chain;

Fig. 7 is a view corresponding to Fig. 6 showing one clutch operating to release the tube frame from the chain;

Fig. 8 is a detail perspective view of a clutch;

Fig. 9 is a detail elevation view of the linkage effective to close the clutches on the tube frames and indicates the mechanism as viewed from the line 9—9 of Fig. 2;

Fig. 10 is an elevation view of the transferring mechanism as seen from the shuttle side indicating certain cams to be described;

Fig. 11 is a detail elevation view of the cam operative to close the clutches on the tube frames through the linkage of Fig. 9;

Fig. 12 is a similar view of a circular disc cam employed to maintain the clutches in engagement with the tube frames during the entire cycle for certain purposes;

Fig. 13 is a view of a modified form of cam employed to raise and lower the clutches, and

Fig. 14 is a detail of a cam employed to tilt the clutches.

As indicated in Figs. 1 and 2 of the drawings, 25 the loom is of the Axminster type and has the usual take-up roll 1 disposed in front of the breast plate 2 to the rear of which reciprocates the lay 3 operated through the linkage 4 and 5 by a cam on the cam-shaft 6 in the usual manner. The needle is indicated at 7 and the shuttle at 8.

The main shaft 6 carries on the needle side a bevel gear 10 meshing with a bevel gear 11 secured to the end of a shaft 12 containing universal joints 13 and connected through the gearing in housing 15 with the shaft 20 which drives the spool chains 21. Within the housing 15 is a bevel gear 22 fixed to shaft 12 and in constant mesh with bevel gears 24 and 25 which are loosely 30 mounted on shaft 20. The bevel gears 24 and 25 have toothed clutch faces 26 and 27, co-operating with which is the slidable clutch member 30 splined to the shaft 20 between the clutch faces 26 and 27. The clutch 30 is grooved on 35 its periphery at 31 to receive the trunnions 32 (Fig. 2) on a forked arm 33 shifted by hand lever 34 in an obvious manner to shift clutch 30 into selective engagement with clutch face 26 or 27 to rotate shaft 20 either forward or 40 reverse relative to the loom shaft 6. Shaft 20 carries fixed to it, on both the needle and shuttle sides of the loom, gears 35 which, as indicated in Fig. 4, mesh with gears 36 and 37 on shafts 40 and 41, respectively. The shafts 40 and 41 45

50

55

55

carry fixed to them at opposite ends the three-toothed sprockets 50 and 51 (see also Fig. 5) around which sprockets pass the two spool chains 21 carrying the spools and tube frames indicated generally at 60.

The capacity for reversing the direction of rotation of shaft 20 relative to the loom shaft 6, by clutch 30, is for reversing the direction of feed of the spool chain 21 so that after weaving one-half of a rug, the same tube frames delivered in reverse order to the weaving point, may be utilized to weave the remaining half of the rug.

In the train of gears connecting the loom shaft 6 and the chain driving shaft 20 there is a speed reduction of three to one so that the shaft 20 rotates one-third as fast as the loom shaft 6. The shafts 40 and 41 rotate at the same speed as that of shaft 20. To correlate the initial position of the chains 21 relative to that of the loom shaft 6 for either forward or reverse movement of the chains, each of the clutch members 31, 26 and 27 has three teeth.

As will appear, chains 21 move continuously during the weaving, rather than intermittently as heretofore, and when the chains move in the direction of the arrow in Fig. 5, the tube frame 60a, for example, will be taken from the link 61 when it is in the position indicated in Fig. 5 and will be returned to the link 61 when that link, which is moving continuously, has advanced to the position there indicated for the link 62. My purpose in providing two sprockets 50 and 51 on separate shafts rather than a single sprocket, disposed at the lowermost point of each chain, as heretofore commonly employed, is to provide a substantially horizontally moving chain course near the weaving point having two or more tube frames to be acted upon by the transferring mechanism.

The mechanism for holding the tube frames in the chains and for releasing the tube frames from the chains is of the usual character and comprises a pair of box-shaped so-called clutch members 70 shown in Fig. 8, one on each side of the loom, and each pivoted at 71 to the end of a clutch arm 72 provided on both the needle and shuttle sides of the loom. To move the clutches 70 toward and away from the ends of the tube frames for the purpose respectively of disengaging a tube frame from the chains and releasing to the chains a tube frame which has been returned, each arm 72 is pivoted at 73 to a member 74 and the rear of each arm 72 is connected by a link 75 to a lever 76 pivoted at 77 to a strap 100 fixed to shaft 78 secured at its opposite ends to the opposite members 74 (see also Fig. 9). The lever 76 is swung by link 80 pivoted at 79 to the lever and at 81 to one arm of a bellcrank lever 82 rotatably mounted on the pivot 86 carried by a boss 87 projecting from the loom frame. From the other arm of the bell crank lever extends the link 84 which, as indicated in Figs. 1, 10 and 11, extends to an arm 83 pivoted to shaft 105 and having a follower 88 riding on a cam 89 fixed to the loom shaft 6. The cam 89 has a low portion 89a and a high portion 89b. When follower 88 is on low portion 89a, as indicated, the clutches 70 are closed on the ends of a tube frame and the 70 clutches are opened by elevation of the follower by high portion 89b of the cam which effects counter-clockwise movement of lever 76 (Fig. 9) resulting in inward swinging of the rear ends of clutch arms 72 and an outward swinging of 75 their front ends carrying the clutches 70.

This movement of the clutches co-operates with fastening elements on the ends of the tube frames in the manner indicated in Figs. 6 and 7. Each tube frame 60 carries at each end an upwardly extending bracket 90 having a tongue 96 of a width and breadth to be received freely between the pair of link elements 21a and 21b forming a link of the chain and the bracket carries riveted to it at 91 a spring latch 92 having a shoulder 93 which, because of the outward resilience of the spring latch 92, holds the tube frame 60 in the links 21a and 21b by abutment of the shoulder 93 with the link element 21a. As indicated in Fig. 7, the clutch 70, upon being moved inwardly against the end of the tube frame 60 in the manner above described, presses inwardly on the spring latch 92 to release the shoulder 93 thereof to release the tube frame from the chain. I have indicated such release by showing the links 21a and 21b as slightly elevated in Fig. 7 from their position in Fig. 6, but this relative movement has been effected by the released tube frame 60 having been carried downwardly and toward the weaving point by the clutches 70 by certain mechanism now to be described.

The members 74 which support the clutch arms 72 at the pivots 73 are fixed to opposite ends of the shaft 78 as above described, and they are swung vertically about the axis of shaft 78 by a rod 101 (Fig. 10) pivoted at 102 to the member 74 on the shuttle side of the loom and at its other extremity pivoted at 103 to a lever 104 loosely mounted on shaft 105. The lever 104 carries a cam follower 106 riding on a cam 110, the details of the configuration of which will be described more fully below but which in general is effective to elevate and depress the arms 74 in an amount sufficient to carry the tube frames, released from the chains as above described, to the weaving point and return.

As stated above, the chains 21 move continuously during the weaving operation and, assuming the chains to be progressing in the direction indicated by the arrow in Fig. 5, the link 61 of the chain will advance from its position indicated to the position now occupied by link 62 while tube frame 60a is being taken from the chain, delivered to the weaving point and returned to the chains. To provide this necessary movement of the clutch members 70 toward the front and rear of the loom, I mount the shaft 78 to which the members 74 carrying the clutches are secured, on levers 120 secured to a shaft 121 extending across the loom and journaled in the loom frame. Rotational movement of the shaft 121 for the purpose of swinging the clutches 70 toward the front and rear of the loom is effected by a lever 125 secured to the shaft 121, which lever is pivoted at 128 to a link 126 which is in turn pivoted at 127 (see also Fig. 3) to one end of a lever 130, pivoted intermediate its ends at 131 and carrying at its forward end a cam follower 132 riding on a cam 135. The cam 135 is fixed to and driven by the aforesaid shaft 20 and, with the chain progressing in the direction indicated by the arrow will rotate counter-clockwise as indicated.

With the parts in their positions indicated in full lines, the tube frame 60 is in the weaving position both in Figs. 3 and 5, although, it should be noted that in Fig. 5, for clearness, the chain is illustrated in the position it occupies when receiving a tube frame. Taking the center of the pivot 71 (Fig. 3) as a reference point by 75

which to trace the movements of the tube frame as it is taken from the chain, wiped in and returned, this pivot will start at the position $71a$, when the tube frame is being released from the 5 chain, and will move along the arc 140 to the full line weaving position 71 , the arc being the resultant of the forward movement effected by the cam 135 and the downward movement effected by the cam 110 (Fig. 10). After the wipe in 10 and beat up of one or more weft shots, the tube frame 60 will be lifted to unwind yarn from the spool, to the point $71b$, where the yarn is cut, after which the tube frame is returned to the chain at $71c$ along the arc 141 . Thereafter, the 15 clutches 70 will be opened to release the tube frame to the chain, after which the reference point will be moved to the $71a$ position along the arc 142 to take the next tube frame from the chain and the cycle is repeated.

20 As stated, the full line positions of the cam follower 132 (Fig. 3) and the linkage connecting it to the clutches indicate their positions when the tube frame is at the weaving point and it will be observed that the follower 132 rests on 25 an elongated dwell at 135 . After a slight pause of the follower during which the frame is lifted to $71b$ for the draw-off and cut, the follower will be elevated by a rise $135c$ to move the several links and pivot 71 from their full line to their C positions. The high portion $135c$ of the cam has a 30 sufficient dwell to allow for opening of the clutches to release the spool to the chain, after which the cam follower 132 descends to the lowest portion $135a$ of the cam, through the influence of 35 a spring 165 connecting the frame and the bell crank arm 125 , to move the parts to their a positions, thereby moving the clutches to take the next tube frame from the chains, after which the parts move to their full line positions, the necessary 40 forward movement of the point 71 being effected by rise of the cam follower on the cam portion 135 . The cycle is then repeated and it will be observed that one cycle occupies one-third of a revolution of cam 135 in accordance with 45 the three to one speed reduction between loom shaft 6 and shaft 20 carrying cam 135 .

The vertical components of the movement of the pivot point 71 are effected in the customary manner by the cam 110 (Fig. 10) and as there indicated, the roller 106 is resting on the low portion 110 of the cam when the tube frame is at the weaving point. The lifting of the tube frame for unwinding and cutting off of the yarn is effected by the rise $110b$ of the cam and the 55 elevation of the arms to the chain is indicated diagrammatically at $110c$ on the cam. The details of the construction of this cam are as usual and are only diagrammatically indicated in the drawings.

60 The cam 89 , shown in Fig. 11, which effects the opening and closing of the clutches on the ends of the tube frames, is secured to the shaft 6 in the position relative to cam 110 , indicated in Fig. 10, so that the rise $89b$ which opens the 65 clutches is effective at the interval in the cycle when the rise $110c$ has raised the clutches to the chains.

When nearing the end of the yarn on the spools, the yarn on a few of the spools will frequently become exhausted before the yarn runs out on the remaining spools. It is customary in that event to continue the weaving and to supply the missing row of pile tufts which was intended to come from an empty spool by inserting an additional row of tufts from an adjacent

spool still having yarn. Although this will distort the pattern somewhat, the practice is not objectionable unless carried to extremes.

For this purpose I provide for a double tuft row insertion from any given tube frame by a 5 shifting of the cam followers 106 and 88 onto a pair of cams which repeat the weaving with the same tube frame. As indicated in Fig. 1, the loom shaft 6 carries, adjacent the cam 110 , a second cam $110s$ and, adjacent the cam 89 , a 10 second cam $89s$.

The shaft 105 , on which the cam follower levers 88 and 106 are pivoted, has collars 170 to prevent longitudinal movement of the cam follower levers relative to the shaft and the shaft is slidably 15 mounted in the frame of the loom. The end of the shaft, as indicated at 171 , has pivoted to it the lower end of a depending lever 172 fixed to a shaft 173 to which a shift lever 174 is also secured. With the lever 174 in the full line position of Fig. 1, the cam followers 106 and 88 will 20 rest on the cams 110 and 89 for the normal running cycle of the loom. To cut in a tube frame twice to replace an exhausted frame, the lever 174 is shifted to the left as indicated in dot-dash 25 lines which will shift the cam followers 106 and 88 to the cams $110s$ and $89s$. The cam $110s$, as indicated in Fig. 13, has a low portion $110t$ of the same height as the low portion 110 of the cam of Fig. 10 and it has a rise $110r$ which elevates the follower 106 the same amount as the rise $110b$ of cam 110 . In cam $110s$, however, the rise $110y$, corresponding in length to the rise $110c$ of cam 110 raises the tube frame from the $71b$ position toward the chain by an amount 30 which, while insufficient to return the tube frame to the chains, yet is sufficient to expose the weave for inspection, if desired, by the operative.

The cam follower 88 which controls the opening and closing of the clutches is also shifted to 40 maintain the clutches in closed position during the entire loom cycle. For this purpose the cam $89s$ (Fig. 12) consists merely of a circular disc of a radius corresponding to that of the low portion $89a$ on cam 89 .

45 During this repeat operation of any given tube frame, the chain travel continues and the empty tube frame in the chain behind the frame which is cut in twice is removed manually from the chain to make room for the return to the chain of the tube frame which was used twice. The lever 174 is then shifted to its full line position and thereafter the normal sequence of operation obtains.

50 As is well known, it is customary to tilt the tube frame 60 during the wiping in operation of the tuft yarn. As indicated in Fig. 5, the clutches 70 which, as stated, are pivoted at 71 , are pivotally connected at 200 to a rod 201 on both sides of the loom, each of which rods is 55 pivoted at 202 to a lever 203 fixed to a shaft 212 whose opposite ends are journalled in the lower ends of levers 120 . Near the shuttle side, Fig. 10, the shaft 212 has fixed to it a lever 213 which is elevated and depressed by a lever 204 60 leading to a lever 205 (Fig. 14) pivoted at 207 and having a follower 206 engaging cam 210 . Elevation of the follower 206 by the cam 210 will tilt the clutches 70 and tube frame in a clockwise direction about the pivot 70 as viewed 65 in Fig. 10 and in a counter-clockwise direction about that pivot as viewed in Figs. 5 and 3. The major portion 214 of the cam is of constant radius for a dwell but a rise 213 is provided for 70 tilting the clutches during the wipe-in.

I have found that apparatus constructed as above described operates effectively for the purpose intended of correlating, with the weaving cycle, a continuous movement of the tube frame carrying chains. In my apparatus there is sufficient play between the links and the tube frame supporting brackets to permit the withdrawal and insertion of tube frames while the chains are moving. However, if necessary, a slight movement of 10 the clutches with the chains can readily be effected by providing the necessary additional cam portions on the surface of cam 135.

It will be noted that when the direction of travel of the chain carrier is reversed to reverse 15 the order of presenting the tube frames, the rotation of cam 135 is also reversed so that the movement of the clutches horizontally is correlated to the reversed direction of travel of the carrier. However, the main camshaft 6 always 20 rotates in the same direction and thereby the raising and lowering of the clutch arms 74, the opening and closing of the clutches and the tilting of the clutches for the wipe-in, are unaffected 25 in their sequence of operations by the reversal of the shaft 29 driving the chains and the cam 135.

I claim:

1. In an Axminster loom, apparatus for continuously operating the chain carrier and delivering tube frames to the weaving point, comprising a 30 chain carrier having a plurality of link sections adapted to carry tube frames, means for advancing the carrier continuously at a constant rate of speed throughout its entire length, transferring mechanism for conveying tube frames from the 35 carrier to the weaving point and return, and means to move the transferring mechanism to one position adjacent the carrier for taking a tube frame from a carrier section and to a different position adjacent the carrier for returning the 40 tube frame to the same carrier section while said carrier section is advancing continuously.

2. In an Axminster loom, apparatus for continuously operating the chain carrier and delivering tube frames to the weaving point, comprising a 45 chain carrier having a plurality of link sections each adapted to carry a single tube frame, means guiding the carrier in a substantially horizontal path over the weaving point, continuously operating driving means advancing the carrier without stoppage, transferring mechanism, means for moving the transferring mechanism in a substantially vertical direction between the carrier and the weaving point for conveying a tube frame from the carrier to the weaving point and return, and means for moving the transferring mechanism in a substantially horizontal direction to direct the said mechanism to one predetermined position adjacent the carrier for taking a 50 tube frame from a carrier section and to another predetermined position adjacent the carrier for returning the tube frame to the same carrier section while said carrier section is advancing continuously.

3. In an Axminster loom, apparatus for continuously operating the chain carrier and delivering tube frames to the weaving point, comprising a 55 chain carrier having a plurality of link sections each adapted to carry a single tube frame, continuously operating driving means to advance the carrier without stoppage, transferring mechanism, means pivotally supporting the transferring mechanism for a substantially vertical swinging movement thereof between the carrier and the weaving point below the carrier for conveying a 60 tube frame from the carrier to the weaving point 70

and return, means for swinging the transferring mechanism about the said pivot means, and means for moving the said pivot means horizontally for guiding the movement of the transferring mechanism to one position adjacent the carrier for taking a tube frame from a carrier section and to a different position adjacent the carrier for returning the tube frame to the same carrier section while said carrier section is advancing continuously. 10

4. In an Axminster loom, adapted to weave reverse patterns, apparatus for continuously operating the chain carrier and delivering tube frames to the weaving point, comprising a chain carrier having a plurality of link sections each adapted to carry a single tube frame, continuously operating driving means to advance the carrier with a continuous movement, transferring mechanism, means for moving the transferring mechanism between the carrier and the weaving point for 20 the wipe in, draw off and return of the tube frame to the carrier, means guiding the movement of the transferring mechanism to present the transferring mechanism to one predetermined position adjacent the carrier, prior to the wipe in, 25 to take a tube frame from a carrier section and to a second position adjacent the carrier, after the wipe in, for returning the tube frame to the same carrier section, while said carrier section is advancing continuously, means for reversing the 30 direction of the said continuous movement of the carrier to reverse the order in which the tube frames are presented to the transferring mechanism, selectively operable means for reversing, relative to the wipe in, the order of the said 35 positions adjacent the carrier in which said transferring mechanism is presented to the carrier so that the transferring mechanism is guided to the second of said predetermined positions to take a tube frame from a carrier section and to the first 40 of said positions to return the tube frame to the same carrier section, while said carrier section is advancing continuously in said reversed direction.

5. In an Axminster loom, apparatus for delivering tube frames to the weaving point, comprising a 45 chain carrier adapted to carry a supply of tube frames, driving mechanism advancing the carrier continuously and without stoppage, transferring mechanism, and means moving the transferring mechanism between the carrier and weaving point 50 to take a tube frame from a link and return it to the same link from which it was taken, of a continuously moving portion of the carrier.

6. In an Axminster loom, apparatus for delivering tube frames to the weaving point, comprising a 55 chain carrier adapted to carry a supply of tube frames, driving mechanism advancing the carrier continuously and without stoppage, mechanism for transferring tube frames between the carrier and weaving point, means moving the 60 transferring mechanism from the carrier toward the weaving point and return, and means coordinating said movement of the transferring mechanism with the continuous advance of the carrier to return the tube frames to the same continuously moving portions of the carrier from which they were taken. 65

7. In an Axminster loom, apparatus for delivering tube frames to the weaving point, comprising a chain carrier adapted to carry a supply of 70 tube frames, guides directing the carrier in a substantially horizontal path over the weaving point, driving mechanism advancing the carrier continuously and without stoppage, transferring mechanism, means for moving the transferring mech- 75

anism vertically between the carrier and the weaving point and means imparting to the transferring mechanism and the carrier a relative horizontal movement whereby to return tube frames 5 to the same continuously moving portions of the carrier from which they were taken.

8. In an Axminster loom, apparatus for delivering tube frames to the weaving point, comprising a chain carrier adapted to carry a supply of 10 tube frames, driving mechanism advancing the carrier continuously and without stoppage, transferring mechanism for conveying tube frames from the carrier to the weaving point and return, means directing the transferring mechanism to a 15 predetermined position adjacent a continuously moving portion of the carrier for taking a tube frame therefrom for delivery to the weaving point, means retracting the transferring mechanism toward the carrier for returning a tube frame 20 thereto, and means relatively shifting the transferring mechanism and the carrier to direct the transferring mechanism, during such retraction, to the same continuously moving portion of the carrier to return the tube frame thereto.

25 9. In an Axminster loom, apparatus for delivering tube frames to the weaving point, comprising a chain carrier adapted to carry a supply of tube frames, sprockets guiding the carrier in a substantially horizontal path over the weaving 30 point, driving mechanism advancing the carrier continuously at a constant rate of speed throughout its entire length, transferring mechanism for conveying tube frames from the carrier to the weaving point and return, means directing the 35 transferring mechanism to a predetermined position relative to said sprockets for taking a tube frame from the carrier for delivery to the weaving point, means retracting the transferring mechanism toward the carrier for returning a 40 tube frame thereto, and means relatively shifting the transferring mechanism and the carrier to direct the transferring mechanism, during such retraction, to another predetermined position 45 with relation to the sprockets for returning the tube frame to the carrier while the carrier is moving continuously.

10. In an Axminster loom, apparatus for delivering tube frames to the weaving point, comprising a chain carrier adapted to carry a supply 50 of tube frames, guides directing the carrier in a substantially horizontal path over the weaving point, driving mechanism advancing the carrier, through said horizontal path, continuously and at a constant predetermined rate of speed, transferring mechanism, means for moving the transferring mechanism vertically to convey tube frames from the carrier to the weaving point and return, means imparting to the transferring mechanism, during the interval between the taking 55 of a tube frame from the carrier and returning it thereto, a horizontal movement in the direction and through the distance of advance of the carrier during such interval and means for moving the transferring mechanism in the opposite horizontal direction after it has returned the tube frame to the carrier, to position the transferring mechanism to take the next successive tube frame therefrom.

11. In an Axminster loom adapted to weave 70 reverse patterns, apparatus for delivering tube frames to the weaving point, comprising a chain carrier adapted to carry a supply of tube frames, guides directing the carrier in a substantially horizontal path over the weaving point, driving 75 mechanism advancing the carrier, through said

horizontal path, continuously and at a constant predetermined rate of speed, transferring mechanism, means for moving the transferring mechanism vertically to convey tube frames from the carrier to the weaving point and return, means 5 for imparting to the transferring mechanism during the interval between the taking of a tube frame from the carrier and returning it thereto, a horizontal movement in the direction and through the distance of advance of the carrier 10 during such interval, means for moving the transferring mechanism in the opposite horizontal direction after it has returned the tube frame to the carrier to position the transferring mechanism to take the next successive tube frame therefrom, means for reversing the direction of advance of the carrier through said horizontal path 15 to weave reverse patterns and means for reversing the said directions of both of said horizontal movements of the transferring mechanism to coordinate with said reverse direction of the carrier.

12. The steps in the method of weaving an Axminster pile fabric which consists in continuously advancing a supply of pile yarn tube frames at a constant rate of speed into and through a transferring station above the weaving point, taking successive individual tube frames from one point in said station for delivery to the weaving point and returning tube frames to another point 30 in said station without interrupting the constant rate of advance of the supply through said station.

13. In an Axminster loom, apparatus for delivering tube frames to the weaving point, comprising a chain carrier adapted to carry a supply of tube frames, driving mechanism advancing the carrier horizontally over the weaving point continuously and without stoppage, transferring mechanism having clutches to take tube frames 40 from the carrier, means for moving the transferring mechanism vertically between the carrier and the weaving point, means imparting to the transferring mechanism and the carrier a relative horizontal movement to coordinate the vertical movement of the transferring mechanism 45 with the continuous advance of the horizontal stretch of said carrier, means selectively operable after the wipe-in of a tube frame for imparting to the transferring mechanism a limited vertical movement sufficient to repeat the wipe-in 50 with an individual tube frame without returning it to the carrier, and means for maintaining the said clutches in closed position during such repeated wipe-in.

14. In an Axminster loom, as means for continuously operating the chain carrier, the combination of a chain carrier having a plurality of link sections each adapted to carry a single tube frame, continuously operated driving means to 60 advance the entire carrier with a continuous movement, transferring mechanism, means for moving the transferring mechanism to take a tube frame from the carrier, means selectively operable after a tube frame has been taken from 65 the carrier for moving the transferring mechanism with tube frame repeatedly in a limited amount sufficient for a number of wiping-in and drawing-off operations but insufficient to return the tube frame to the carrier, and means to return the tube frame to the carrier thereafter, all while the carrier is advancing continuously.

15. In an Axminster loom, as means for continuously operating the chain carrier, the combination of a chain carrier having a plurality 75

of link sections each adapted to carry a single tube frame, continuously operated driving means to advance the entire carrier with a continuous movement, transferring mechanism, means for 5 moving the transferring mechanism to take a tube frame from a section of the carrier, means selectively operable after a tube frame has been taken from the carrier for moving the transferring mechanism with tube frame repeatedly in 10 a limited amount sufficient for a number of wiping-in and drawing-off operations, but insufficient to return the tube frame to the carrier, and means to return the tube frame to a different section of the carrier, all while the carrier is advancing continuously.

16. The mechanism as defined in claim 4 in which said selectively operable means for reversing, relative to the wipe in, the order of the said

positions adjacent the carrier in which said transferring mechanism is presented to the carrier operates independently and without affecting the operation of said means for moving the transferring mechanism between the carrier and 5 the weaving point for the wipe in, draw off and return of the tube frame to the carrier.

17. A device as defined in claim 6 which also has selectively operable means for advancing the carrier continuously and without stoppage but in 10 the reverse direction, and means coordinating, with the continuous advance of the carrier in said reverse direction, the said movement of the transferring mechanism to return the tube frames to the same continuously moving portions 15 of the carrier from which they were taken.

JOSEPH A. COYLE.
